[57] CLAIM

The ornamental design for a panel carrier, as shown and described.

DESCRIPTION

FIG. 1 is a top plan view of a panel carrier embodying my new design;

FIG. 2 is a front elevational view thereof;

FIG. 3 is a rear elevational view thereof;

FIG. 4 is a bottom plan view thereof; and

FIG. 5 is a side elevation view thereof.

A side elevational view taken from the side opposite that shown in FIG. 5 is essentially a mirror image thereof.
